UNITED STATES PATENT OFFICE.

FRANZ JOSEPH SCHMITTNER, OF GERMANIA, PENNSYLVANIA.

TRIP-STAKE AND BOLSTER FOR LOGGING-CARS.

No. 900,040.

Specification of Letters Patent. Patented Sept. 29, 1908.

Application filed June 13, 1908. Serial No. 438,438.

To all whom it may concern:

Be it known that I, FRANZ JOSEPH SCHMITTNER, a citizen of the United States, residing at Germania, in the county of Potter 5 and State of Pennsylvania, have invented certain new and useful Improvements in Trip-Stakes and Bolsters for Logging-Cars; and I do hereby declare the following to be a full, clear, and exact description of the invention, such as will enable others skilled in the art to which it appertains to make and use the same.

My invention relates to logging cars, but more particularly to bolsters and end stakes 15 therefor, and to means for tripping said stakes for the release and discharge of logs from one side of the car or the other at will of the operator.

For its object this invention contemplates 20 the production of a bolster equipment which is at once simple, cheap, and durable in its construction, easily manipulated and efficient in its operation.

As a further object this invention contemplates the production of means whereby 25 logging cars are more readily and securely loaded than heretofore, means whereby safe transportation of a cargo of logs is insured, means whereby the use and vexatious annoyances of logging chains is avoided, and 30 what is of even greater importance, the lives and limbs of employees protected.

The invention will be hereinafter particularly described and pointed out in the claims 35 following.

In the accompanying drawings which form part of this application and whereon corresponding reference numerals indicate like parts in the several views: Figure 1 represents in end elevation one complete bolster 40 with its trip stakes in position for loading, the figure being broken away at its center for economy of space upon the sheet. Fig. 2 is a longitudinal sectional view of one bolster 45 broken centrally as in Fig. 1, and taken upon the line $x-x$ of Fig. 3. Fig. 3 is a horizontal section, also broken away centrally, and taken on the line $y-y$ of Fig. 2. Fig. 4 is a bottom plan view of the trip stakes shown in 50 Figs. 1, 2 and 3, and Fig. 5 is a modified form of trip stake in side elevation.

Reference being had to the drawings and numerals thereon, 1, 1 indicates the side sills of bolster, and 2 the intervening space-timber or filler, while 3, 3 indicate space blocks at ends of the structure these parts 1,

2 and 3 constituting the body of the bolster and securely bolted together as shown. By this arrangement two end wells or recesses 4, 4 are produced as a suitable housing for the 60 movable operating elements of my invention. Said wells or recesses 4, 4 are faced and reinforced by sheet metal wear plates 5, 5 flanged at their outer ends over sills 1, 1 as best shown by Fig. 3. 65

The bolsters at opposite ends of a car are counterparts one of the other, and likewise opposite ends of each bolster are the same, so that a description of one end of one bolster will be understood to apply to both and is 70 sufficient for present purposes.

Journalized in each well 4 between plates 5, 5 which also serve as guide plates therefor is an ejector 6 preferably of cast steel, having a substantially angular spur or projecting base 7, pivotally mounted as upon a through bolt 8 near its base and provided upon its inner edge with a projecting fin 9 as best shown by Fig. 2. Pivotally connected to said fin 9 is one member 10 of a toggle lever, 75 bifurcated at both ends and at its inner end pivotally connected to the other toggle member 11 which latter, in turn, is pivotally mounted upon a through bolt 12. To the toggle 10, 11 is connected a floating lever 13 80 also preferably bifurcated at both ends and at its lower end connecting with a short rock-lever 14 keyed upon a rock-shaft 15 passing transversely through the structure. Upon the projecting end of said shaft 15 at the side of one sill 1, is keyed a trip-lever 16 protected by a flanged shield 17 above, and fitted at its upper end with a trip-rod 18 extending to the opposite end of the bolster, as 85 shown by Figs. 1 and 3. The said trip-rod 18 is guided in suitable eyes or staples 19, and terminates in a pull-handle 20, adapted to be secured in normal or locked position over a staple or eye-bolt 21 by agency of a pin 22 or a padlock. 90

At opposite ends of each bolster are trip-stakes or log retaining stakes 23 made of any suitable material, but as a matter of convenience preferably of hard wood. The lower end of stakes 23 are sheathed in a sheet steel outer casing 24 to protect them against wear and to facilitate the operation of ejecting them when desired. Casing 24 extends slightly above the bolster surface, and at its lower end is broken by side openings 25 and 105 a bottom opening 26 for purposes that will later appear. These stakes are loosely

chained or otherwise secured to their respective bolsters as at 27 to prevent loss, and when in operative position as shown at the left end of Fig. 2, stand vertically between the inner edge of space block 3 and the plane outer surface of the oscillatory ejector 6, the angular spur base 7 projecting beneath.

The surface of bolster is covered by a single plate of sheet iron 28 slotted centrally 10 at its ends as at 29 to permit the introduction and ejection of trip-stakes 23; while beneath said slots 29 resting in suitable guides (not shown) on the surface of sills 1, 1, are reciprocating covers 30 or partial closures 15 for said slots 29. These covers 30 are automatic in their action being connected to the fin 9 of ejector 6 by a rigid connecting rod 31 as shown by Fig. 2.

This being a description of my invention, 20 its operation is as follows: The car to be loaded is first fitted with trip-stakes 23 as shown by Fig. 1, an ordinary log-loader upon temporary tracks upon the floor of an adjacent car of a logging train is next backed into 25 position for service as usual, logs are then loaded between corresponding stakes 23 of both bolsters, said stakes being locked and securely retained in their normal or vertical positions by the alinement of toggle members 30 10, 11 and their actuating mechanism. Thus a cargo of logs for the mill, or other destinations, without the use of log loading chains, may be transported with safety regardless of the usual rough conditions of logging roads. 35 Upon arriving at its destination a car fitted with my improved trip-stakes and bolsters is speedily and safely unloaded as follows: Engaging the pull handle 20 of trip-rod 18, with the hook member of an ordinary pike 40 lever (not shown), the operator forcibly reciprocates said rod, causing a partial rotation of rock-shaft 15 by agency of the intervening trip-lever 16. As a consequence, the lever 14 keyed upon and moving with shaft 45 15 pulls downward upon floating lever 13 disturbing the locking alinement of toggle members 10, 11, whereupon the latter assume the position indicated at the right hand end of Fig. 2, thus tilting the corresponding 50 ejector 6 upon its pivotal support 8. Simultaneously the corresponding slides 30 are withdrawn, and the corresponding trip-stakes 23 released from their normally clamped and locked positions are quickly 55 elevated by the underlying spur 7. Aided now by the lateral pressure of the load, stakes 23 unlocked as aforesaid are instantly ejected thus releasing the logs upon the opposite side of the car from that occupied by 60 the operator, thereby insuring his safety.

During the tripping operation aforesaid slides 30 upon the discharging side of the car are automatically opened to facilitate ejection of the stakes 23, but at all other times 65 they stand closed for the purpose of exclud-

ing foreign matter from their respective wells 4, and for like purposes the flanged shields 17 are provided over and above the trip-levers 16.

If perchance a stake 23 should in any manner be broken, a new stake may readily be substituted, and to this end the openings 25 and 26 in metallic casing 24 are designed and adapted to assist in clearing said casing of the 70 within contained portion of said broken stake. 75

This being a description of my invention in its preferred form and arrangement it should be noted that I do not confine myself thereto, as various changes in the arrangement, construction and combination of parts 80 may be made and substituted for those herein shown and described without departing from the spirit and teachings of my invention. For example, my improved bolster may be economically manufactured entirely 85 from structural iron flanged as usual for purposes of strength and lightness. The trip-stake 23 may if desired be cast or formed solid, as indicated by modified Fig. 5, and in like manner other contemplated changes 90 will readily be suggested to persons skilled in the art.

Having thus described my invention, what I claim and desire to secure by Letters Patent is:

1. In a bolster for logging cars, the combination with trip-stakes, of means operated from the opposite side of the car for releasing and ejecting said stakes, substantially as described. 95
2. In a bolster for logging cars, the combination with a trip-stake, of an oscillatory ejector, and a trip-rod operated from the opposite side of the car for actuating said ejector to cast out said stake, substantially 100 as described.
3. In a bolster for logging cars, the combination with a trip-stake, of an oscillatory ejector, a trip-lever, suitable connections between said ejector and lever, and a trip-rod operated from the opposite side of said car for actuating said trip-lever to cast out said stake, substantially as described. 105
4. In a bolster for logging cars, the combination with trip-stakes on opposite ends thereof, of means for ejecting either of said stakes from the side of the car opposite that occupied by said stake, said means comprising oppositely disposed trip rods, trip-levers connected with said rods, and suitably connected ejectors combined and arranged to cast out their respective stakes, substantially 110 as described. 115
5. In a bolster for logging cars, the combination with trip-stakes, of an oscillatory ejector adjacent to each of said stakes, a toggle-lever normally resisting movement of said ejectors, a trip-lever for actuating each of said toggles to oscillate their respective 120 ejectors, substantially as described. 125

6. In a bolster for logging cars, the combination with tripping-stakes, of duplicate mechanism for releasing and ejecting said stakes comprising, an oscillatory ejector having a projecting base, a toggle-lever for actuating said ejector, a trip-lever, a floating link between said levers, and a trip-rod operated from the opposite side of the car for actuating said ejector, substantially as described.
- 10 7. In a bolster for logging cars, the combination with side sills, an intermediate filler member, and end space-blocks, of trip-stakes

adjacent to said space-blocks, means located between said sills for releasing and ejecting said trip-stakes, and a trip-rod adapted to be 15 operated from the opposite side of the car for actuating the said releasing and ejecting means, substantially as described.

In testimony whereof I affix my signature, in presence of two subscribing witnesses. 20
